UNITED STATES PATENT OFFICE.

BURT FROST UPHAM, OF BROOKLINE, FRANK R. BELLUCHE, OF MANSFIELD, AND
KURT F. HORNIG, OF AMESBURY, MASSACHUSETTS, ASSIGNEES TO UNITED
PRINTING MACHINERY COMPANY, OF BOSTON, MASSACHUSETTS, A CORPORA-
TION OF MASSACHUSETTS.

MECHANISM FOR TRANSFERRING AND TIMING SHEETS.

Application filed June 21, 1920, Serial No. 390,500. Renewed July 16, 1921. Serial No. 485,401.

To all whom it may concern:

Be it known that we, BURT F. UPHAM, of Brookline, county of Norfolk, Mass.; FRANK R. BELLUCHE, of Mansfield, county of Bristol, Mass.; and KURT F. HORNIG, of Amesbury, county of Essex, Mass., all citizens of the United States, have invented certain new and useful Improvements in Mechanism for Transferring and Timing Sheets; and we hereby declare that the following is a full, clear, and exact description thereof, reference being had to the accompanying drawings, which form part of this specification.

This invention is a novel mechanism for transferring sheets of paper from a machine, such as a printing press, operating thereon to another machine, such as a bronzer, for further operations and for timing the passage of the sheets between the two machines so that the sheets will be properly presented to the second machine, whereby the sheets can be taken from one machine and properly presented to the other machine regardless of small variations, or lack of exact synchronism, in the time required for a cycle of operations by the respective machines.

A great deal of difficulty has been heretofore experienced in printing and bronzing sheets of paper by successive continuous operations, for the reason that it is difficult to operate the two machines in exact synchronism and consequently the sheets printed by the press are not always properly presented to the bronzing machine thus necessitating readjustment and causing delay and inconvenience in the operation of the machines.

By the present invention we have provided sheet transferring and timing means whereby such difficulties as have been heretofore caused by slight variations in time of operation of the printing press and bronzing machine, or failure of exact synchronism of operation, will not affect the proper transfer of the sheets from the press to the bronzing machine, nor the proper presentation of such sheets to the bronzing machine after they are transferred from the printing press.

We will explain one practical embodiment and application of the invention (as adapted to transfer sheets from a printing press to a bronzing machine) with reference to the

accompanying drawings to enable others familiar with the art to readily adapt and use the same; but we do not consider the invention restricted to the specific mechanisms shown; and therefore refer to the claims for summaries of the essentials of the invention, and of the novel features of construction, and the novel combinations of parts, for all of which we desire protection.

In said drawings, Fig. 1 is a diagrammatical longitudinal sectional elevation of a printing press, of a bronzing machine, and of our novel mechanism for transferring sheets from the press to the bronzer.

Fig. 2 is an enlarged detail top plan view of part of the sheet transferring devices.

Fig. 3 is an enlarged detail sectional view on the line 3—3, Fig. 2.

Fig. 4 is an enlarged detail view illustrating the operation of the traveling sheet stops.

Fig. 5 is a detail plan view of Fig. 4.

In Fig. 1 we have indicated a rotary sheet printing press having a plate cylinder P and an impression cylinder I. The printing press may be of any desired construction, or any other suitable mechanism may be employed. The invention is more particularly intended for use in connection with rotary presses.

In the type of press shown the sheets are received from a table T and after being printed are taken from the impression cylinder I by the grippers e on endless carriers E, which carriers run horizontally from a reel R beside the impression cylinder to and under guide rollers R', then up over guide rollers R²; then preferably in a horizontal direction to and over guide rollers R³, then back to and over guide rollers R⁴; then down under guide rollers R⁵; and thence back to the reel R; thus the grippers e travel in an endless circuit.

The grippers e ordinarily transfer the printed sheets S from the impression cylinder I to and over a sheet delivery table in the usual manner; but in the present instance instead of the delivery table the sheets S are delivered from the carriers E onto the upper run of a set of horizontally disposed endless tapes D; which tapes run over guide rollers or pulleys d, d' on shafts 1^a, 1^b which

are journaled in suitable bearings (not shown) attached to the press frame or other convenient support, in a plane below and parallel with the run of the carriers E between the rollers R² and R³.

The tapes D transfer the sheets onto tapes F (Fig. 2) which run over guide pulleys f on shaft 1^b, and over guide pulleys f' on a shaft 1^c, which is journaled in suitable supports at the receiving end of the machine that next operates on the sheet which is indicated in Fig. 1 as a bronzing machine.

The bronzing machine may be of any suitable construction. As shown it has a bronzing cylinder W, provided with grippers w, adapted to take sheets at the proper point and carry them past the usual bronzing devices, and then surrender them to a delivery reel V by which they are transferred into position to be discharged by a fly U onto a receiving table X as indicated in the drawing. The particular make or mechanisms of the printing press and bronzing machine form no part of this invention. The types indicated are well known; and other well known printing and bronzing machines may be used.

At the outer side of the series of tapes F and parallel therewith are endless belts A which are mounted on pulleys a, a', on shafts 1^b and 1^c respectively. The pulleys a, a' are preferably toothed or sprocket pulleys and belts A are preferably sprocket belts, or perforated to engage such sprocket pulleys, so that said pulleys and belts drive the shaft 1^b from the shaft 1^c.

The sheets are delivered by the tapes F onto endless tapes G which run over pulleys g on the shaft 1^c, and over guide pulleys g', adjacent the cylinder W. The tapes G present the sheets to the grippers w of the bronzing cylinder W.

The tapes D, F, and G, and belts A should be driven at a lineal speed twice as fast as the peripheral speed of the bronzing cylinder W; and cylinder W is preferably driven at a peripheral speed slightly faster than the peripheral speed of the impression cylinder I, and lineal speed of the carriers E.

The shaft 1^c is preferably driven from the bronzing machine by any suitable gearing which will cause the belts A, and tapes F, G, and D to travel at about twice the peripheral speed of the bronzing cylinder W, as above stated.

Parallel with and above the shafts 1^b, 1^c, are shafts 1^e, 1^f, which may be journaled in suitable supports (not shown) on the press and bronzing machine frames. Shaft 1^f is preferably geared to the shaft 1^c by gears 1^h, 1ⁱ, as indicated in the drawings.

Extending between the shafts 1^e, 1^f and supported by pulleys b, b' thereon are a series of endless tapes B. The tapes B are preferably mounted on pulleys b' fast on

the shaft 1^f and pulleys b loose on the shaft 1^e, so that tapes B are driven from shaft 1^f at the same speed as belts A and F.

Arranged between and parallel with certain of the tapes B are endless belts C, which preferably are sprocket belts and run over sprockets c fast on shaft 1^e and over sprocket pulleys c' loose on shaft 1^f.

The gear 1^h is preferably a double width gear and meshes with gear 1ⁱ and also with a gear 2^h on a shaft 2^a journaled in bearings on the bronzing machine. On shaft 2^a is mounted a series of pulleys h carrying tapes H, which also run over pulleys h' on a shaft 2 adjacent cylinder W (Fig. 1). Shaft 2 is provided with a gear 2^d meshing with a gear w' on cylinder W, and the gearing being preferably such as will cause the belts H to travel at a lineal speed equal to the peripheral speed of the bronzing cylinder W.

Arranged beside and parallel with tapes H are belts H² which are preferably sprocket belts and run over sprocket pulleys fast on shaft 2, 2^a, and said sprocket belts and pulleys cause gear 2^h to drive shaft 1^c at a speed sufficient to cause the belts A and tapes F, G, B, and D, to travel at twice the peripheral speed of the bronzing cylinder W. Any other suitable means for driving belts H at the speed of the bronzing cylinder may be used.

The shaft 1^e may be driven by means of gears 1^h, 1ⁱ, from a gear 1^j on the shaft 1^a of the guide pulleys R²; or by any other suitable means, so that the belts C will be driven at the same lineal speed as the belt E (or peripheral speed of the impression cylinder I).

To the belts C are attached suitable sheet-stops (such as 3) which are adapted when on the lower run of the belt to project into the path of a sheet lying upon the faster running tapes F (see Figs. 1, 3 and 4) and prevent the tapes F advancing such sheet beyond such sheet stops, which travel at the same speed as the carriers E (i. e. at the peripheral speed of the printing cylinders I, P). These sheet stops however are moved out of the way of the sheet before it reaches the shaft 1^f, so as to permit the sheet to pass from tapes F onto tapes G which rapidly advance the sheet toward the cylinder W; but as the sheets are thus advanced by tapes G they are brought up against the moving sheet stops H' attached to the belt H², which stops travel at exactly the same speed as the periphery of the bronzing cylinder W and will ensure that the forward edge of the sheet is in position to be taken by the grippers w on the bronzing cylinder W at the proper time.

As shown each sheet stop on belt C consists of a finger 3 pivoted at 3^a on a casting 3^b fastened to the belt C and projecting a little to one side thereof (Figs. 3, 4 and 5)

so that the finger 3 lies at one side of the belt. The finger 3 has a cam portion 3^a at its base projecting beyond the pivot, and said cam portion has a part 3^c, which is adapted to engage the periphery of the pulley c as the belt C moves the casting 3^b therarround (see Fig. 4), and part 3^c, riding on the periphery of the sprocket c acts as a cam to throw the finger 3 to a position 10 perpendicular to the belt C, as shown in full lines in Fig. 4, and the finger is held in this position by means of a pin 3^e contained in a socket in an extension 3^f of the casting 3^b, and projected by a spring 3^j in the socket. 15 The finger also has a stop portion 3^l, which is adapted to engage the pin 3^e to arrest the finger in a position perpendicular to belt C (see Fig. 4). To belts A are attached trips 3^x which at 20 the proper time come into contact with the fingers 3 (as shown in full lines in Fig. 4) but owing to the differences in the relative speeds of the belts A and C trip 3^x engage and rock the fingers 3 until the spring 25 pressed bolt 3^g engages the cam portion 3^a whereupon the spring 3^j causes cam 3^a to rock the fingers 3 into the position indicated in dotted lines in Fig. 4, out of the way of the sheet S, which then can pass onto the 30 tapes G, until it is arrested by the stop H'.

Operation.

Preferably there are two sets of sheet stops 3 on belts C, and these belts are of 35 such length and the stops so positioned thereon that one or the other set of stops 3 will always be in position to arrest the forward edge of a sheet S as it is advanced by the tapes D, F, and prevent the same improperly passing between the tapes G and H. There are also preferably two sets of 40 stops H' on the belts H², and one of the stops will always come into position to arrest the leading edge of a sheet S between 45 the shaft 1^c and pulleys g', so that notwithstanding the fact that the sheet is advanced so much more rapidly by the tapes D, F, G, than by the carriers E, and (notwithstanding the fact that the cylinder W is rotated 50 slightly faster than the printing cylinders P, I,) the sheets will always be properly presented to the cylinder W.

In practice the peripheral speed of the cylinder W is preferably slightly faster 55 than the peripheral speed of the printing cylinders P, I and therefore for each revolution of the bronzing cylinder W it makes a slight gain on the printing cylinders P, I. For example, if the bronzing cylinder gains, 60 say one inch per revolution on the printing cylinders, it will ultimately gain a complete revolution on the printing cylinder; and assuming that the bronzing cylinder is 65 50 inches in circumference, for each 50 revolutions of the bronzing cylinder the print-

ing cylinder would only make 49 revolutions. Therefore we provide the sheet stops 3 and H' and the belts A, C, and H² so that when operated as described they will automatically take care of the leading edges of 70 the series of sheets successively delivered from the printing cylinders and insure that 49 sheets will successively be presented to the bronzing cylinder in proper position, but on the 50th revolution the bronzing cylinder would not receive a sheet because 75 there would be none presented thereto at the proper time, but on the next revolution of the bronzing cylinder a sheet would be 80 properly presented thereto and the cycle of 49 operations repeated. For each cycle of operations the stops 3 would arrest the sheets at successively further distances from the tapes G until say the sheet following the 49th would be arrested at such a distance from tapes G as will permit the cylinder W to make one idle revolution before such sheet reaches it. Of course these figures are merely illustrative and not accurate. 90

What we claim is:—

1. In mechanism of the character specified, a first means for operating upon sheets; a second means for operating upon sheets; and sheet transferring means receiving 95 sheets from the first means for operating upon sheets and moving them toward the second means for operating upon sheets; said transferring means moving at approximately twice the speed of the second means 100 for operating upon sheets, and means adapted to retard the movement of the sheets by the transferring means.

2. In mechanism as set forth in claim 1; a sheet carrying means operating at approximately the speed of the sheet transferring means and receiving sheets therefrom; and means adapted to retard the movement of the sheets by said sheet carrying means to substantially accord with the 105 speed of the second means for operating upon sheets.

3. In combination with a first and a second means for operating upon sheets; sheet transferring means comprising endless tapes receiving sheets from the first means for operating on sheets and moving them toward the second means for operating upon sheets; said endless tapes being driven at approximately twice the speed of the second means 120 for operating upon sheets; and means adapted to retard the movement of the sheets upon the said tapes to substantially accord with the speed of said second means for operating upon sheets.

4. In mechanism as set forth in claim 3, a sheet carrying means operating at approximately the speed of the sheet transferring means and receiving sheets therefrom; and means adapted to retard the movement of 130

the sheets by said sheet carrying means to substantially accord with the speed of the second means for operating upon sheets.

5. In mechanism of the character specified; a first means for operating upon sheets; and means for delivering sheets therefrom; a second means for operating upon sheets, and means for feeding sheets thereto; with sheet transferring mechanism receiving 10 sheets from the said delivery means and moving them toward the said feeding means; said transferring means operating at approximately twice the speed of the second sheet operating means; and means adapted 15 to retard the movement of the sheets upon the transferring means.

6. In mechanism as set forth in claim 5; the sheet carrying means for feeding sheets to the second means for operating upon 20 sheets operating at approximately the speed of the sheet transferring means and receiving sheets therefrom; and means cooperating with said sheet carrying means to limit the movement of the sheets thereon to substantially accord with the speed of the second means for operating upon sheets.

7. In combination with a first and a second means for operating upon sheets; sheet transferring mechanism comprising 30 endless tapes receiving sheets from the first means for operating on sheets, and moving them toward the second means for operating upon sheets; said endless tapes being driven at approximately twice the speed of 35 the second means for operating upon sheets; and traveling means moving at the speed of the first means for operating upon sheets and adapted to retard the movement of the sheets upon the tapes to substantially accord with 40 the speed of said second means for operating upon sheets.

8. In mechanism as set forth in claim 7, a sheet-carrying-means for feeding sheets to the second means for operating upon 45 sheets, said carrying means operating at approximately the speed of the sheet transferring means and receiving sheets therefrom; and means cooperating with said sheet carrying means and limiting the movement of 50 the sheets thereon to substantially accord with the speed of the second means for operating upon sheets.

9. In mechanism of the character specified, a first means for operating upon sheets; and a second means for operating upon the sheets; with means for transferring sheets from the first means for operating upon sheets toward the second means for operating upon sheets, said transferring means including 60 endless tapes traveling at approximately twice the speed of the second means for operating upon sheets; and endless belts carrying means adapted to retard the movement of the sheets upon the said tapes.

65 10. In mechanism as set forth in claim

9; a second set of endless tapes operating at approximately twice the speed of the second means for operating upon sheets, and receiving sheets from the first set of endless tapes; and traveling means cooperating with 70 said second set of tapes to retard the movement of sheets thereby to substantially the speed of the second means for operating upon sheets.

11. In mechanism of the character specified, a first means for operating upon sheets and a second means for operating upon sheets; with means for transferring sheets from the first means for operating upon sheets toward the second means for operating upon sheets; said transferring means including endless tapes traveling at approximately twice the speed of the second means for operating upon sheets; and traveling means 80 including endless belts moving at the speed of the first means for operating upon sheets, and stops carried by said belts adapted to retard the movement of the sheets upon the said tapes, substantially as described.

12. In mechanism as set forth in claim 90 11; a second set of endless tapes operating at approximately twice the speed of the second means for operating upon sheets and receiving sheets from the first set of sheet transferring tapes; and traveling sheet stops 95 cooperating with said second set of tapes to limit the movement of the sheets thereon to substantially the speed of the second means for operating upon sheets.

13. In mechanism of the character specified, a first means for operating upon sheets; an endless carrier for delivering sheets therefrom; and a second means for operating upon the sheets; with sheet transferring means comprising endless tapes receiving sheets from the delivery of the first means for operating upon sheets; said endless tapes traveling at approximately twice the speed of the second means for operating upon sheets; endless belts arranged above 100 the fast moving tapes and moving at the speed of the first means for operating upon sheets, and stops carried by said belts adapted to retard the movement of the sheets upon the said tapes, substantially as described.

115 14. In mechanism as set forth in claim 13, a second set of endless tapes operating at approximately twice the speed of the second means for operating upon sheets and receiving sheets from the first set of sheet transferring tapes; and traveling sheet stops 120 cooperating with the second set of tapes to limit the movement of the sheets thereon to substantially the speed of the second means for operating upon sheets.

125 15. In combination with a printing press and a bronzing machine, sheet transferring means receiving sheets from the press and transferring them toward the bronzing machine; said transferring means moving at 130

- approximately twice the speed of the bronzing machine; and means adapted to retard the actual movement of the sheets by the transferring means.
- 6 16. In mechanism as set forth in claim 15, a sheet carrying means operating at approximately the speed of the sheet transferring means and receiving sheets therefrom; and means adapted to retard the movement 10 of the sheets by said sheet carrying means to substantially accord with the peripheral speed of the bronzing machine.
17. In combination with a printing press and a bronzing machine, sheet transferring means comprising endless tapes receiving sheets from the press and delivering them toward the bronzing machine; said endless tapes being driven at approximately twice the speed of the bronzing machine; and means adapted to retard the movement of the sheets upon the said tapes to substantially accord with the speed of said bronzing machine.
18. In mechanism as set forth in claim 17, 25 a sheet carrying means operating at approximately the speed of the sheet transferring means and receiving sheets therefrom, and means adapted to retard the movement of the sheets by said sheet carrying means 30 to accord with the speed of the bronzing machine.
19. In mechanism of the character specified, a rotary printing press for operating upon sheets, and a bronzing machine for operating upon the sheets; with means for transferring sheets from the press toward the bronzing machine; said transferring means including endless tapes traveling at approximately twice the speed of the bronzing machine; and traveling means adapted 40 to retard the movement of the sheets upon the said tapes.
20. In mechanism as set forth in claim 19; 45 a second set of endless tapes operating at approximately twice the speed of the bronzing machine and receiving sheets from the first set of endless tapes; and traveling means cooperating with said second set of tapes to retard the movement of sheets thereby to substantially the speed of the bronzing machine.
21. In mechanism of the character specified, a sheet printing press, means for delivering sheets therefrom; a bronzing machine 55 and means for feeding sheets thereto; with means for transferring sheets from the said delivering means toward the said feeding means; said transferring means including endless tapes traveling at approximately twice the speed of the bronzing machine; and traveling endless belts moving at substantially the speed of the press and stops carried by said belts adapted to retard the movement of the sheets upon the said tapes, substantially as described.
22. In mechanism as set forth in claim 21; the means for feeding sheets to the bronzing machine comprising a second set of endless tapes operating at approximately twice the speed of the bronzing machine and receiving sheets from the sheet transferring tapes; and traveling sheet stops cooperating with said second set of tapes to limit the movement of the sheets thereon to the speed of the bronzing machine.
- 70 23. In mechanism of the character specified, a sheet printing press; an endless carrier for delivering sheets therefrom; and a bronzing machine for operating upon the sheets; with sheet transferring means comprising endless tapes receiving sheets from the said carrier; said endless tapes traveling at approximately twice the speed of the bronzing machine; endless belts arranged above the fast moving tapes and moving at 80 the speed of the first means for operating upon sheets, and stops carried by said belts adapted to retard the movement of the sheets upon the said tapes, substantially as described.
24. In mechanism as set forth in claim 23, a second set of endless tapes operating at approximately twice the speed of the bronzing machine and receiving sheets from the first set of sheet transferring tapes and delivering them to the bronzing machine; and traveling sheet stops cooperating with the second set of tapes to limit the movement of the sheets thereon to the speed of the bronzing machine.
- 95 25. In mechanism of the character specified, an endless belt, a pulley over which the belt passes, a member attached to said belt, and a stop finger pivoted on said member having a portion adapted to engage the surface of the pulley and throw the finger into operative position; and means for returning the finger to inoperative position.
- 100 26. In mechanism as set forth in claim 25; an endless belt parallel with the first belt 110 and moving at a greater speed, and devices on said latter belt adapted to engage the finger and return it to inoperative position.
27. In mechanism as set forth in claim 25; a spring actuated detent carried by said member adapted to hold the finger both in 115 its operative position and in its inoperative position.
28. In mechanism as set forth in claim 26; a spring actuated detent carried by the member adapted to hold the finger in its operative position and in its inoperative position.
- 120 29. In mechanism of the character specified, a first means for operating upon sheets; a second means for operating upon sheets; means receiving sheets from the first means for operating upon sheets and transferring them toward the second means for operating upon sheets; and means adapted to retard 125 130

the movement of the sheets by the transferring means.

30. In mechanism as set forth in claim 29; a sheet carrying means receiving sheets from 5 the sheet transferring means and delivering them to the second means for operating upon sheets at substantially the speed of said second means for operating upon sheets.

31. In combination with a first and a second means for operating upon sheets, sheet transferring means comprising endless tapes receiving sheets from the first means for operating on sheets and delivering them toward the second means for operating upon 15 sheets; and means adapted to retard the movement of the sheets by the transferring means.

32. In mechanism as set forth in claim 31, a sheet carrying means receiving sheets from 20 the sheet transferring means and delivering them to the second means for operating upon sheets at substantially the speed of said second means for operating upon sheets.

33. In mechanism of the character specified, a first means for operating upon sheets; a second means for operating upon sheets; and sheet transferring means receiving sheets from the first means for operating upon sheets and transferring them toward the second means for operating upon 30 sheets; said transferring means moving at greater speed than the second means for operating upon sheets, and means for retarding the movement of the sheets by the transferring means.

34. In mechanism as set forth in claim 33; a sheet carrying means operating at approximately the speed of the sheet transferring means and receiving sheets therefrom; 40 and means adapted to retard the movement of the sheets by said sheet carrying means to substantially accord with the speed of the second means for operating upon sheets.

35. In combination with a first and a second means for operating upon sheets; sheet transferring means comprising endless tapes receiving sheets from the first means for operating on sheets and delivering them to the second means for operating upon sheets; said endless tapes being driven faster than the speed of the second means for operating upon sheets; and means adapted to retard the movement of the sheets upon the said tapes to substantially accord with the speed 50 of said second means for operating upon sheets.

36. In mechanism as set forth in claim 35, a second set of endless sheet carrying tapes operating at approximately the speed 60 of the first set of sheet transferring tapes

and receiving sheets therefrom; and means adapted to retard the movement of the sheets by said second set of tapes to substantially accord with the speed of the second means for operating upon sheets.

65

37. In mechanism as set forth in claim 1, the sheet retarding means operating to slow down the speed of movement of the sheets by the transferring means to accord with the speed of the second means for 70 operating upon sheets before the sheets are delivered to said second means.

38. In mechanism as set forth in claim 5, the sheet retarding means operating to slow down the speed of movement of the sheets 75 by the transferring means to accord with the speed of the second means for operating upon sheets before the sheets are delivered to said second means.

39. In mechanism as set forth in claim 80 9; the sheet retarding means operating to slow down the speed of movement of the sheets by the transferring means to accord with the speed of the second means for operating upon sheets before the sheets are 85 delivered to said second means.

40. In mechanism as set forth in claim 19; the sheet retarding means operating to slow down the speed of movement of the sheets by the transferring means to accord 90 with the speed of the second means for operating upon sheets before the sheets are delivered to said second means.

41. In mechanism as set forth in claim 95 29; the sheet retarding means operating to slow down the speed of movement of the sheets by the transferring means to accord with the speed of the second means for operating upon sheets before the sheets are 100 delivered to said second means.

42. In mechanism as set forth in claim 31, the sheet retarding means operating to slow down the speed of movement of the sheets by the transferring means to accord 105 with the speed of the second means for operating upon sheets before the sheets are delivered to said second means.

43. In mechanism as set forth in claim 33; the sheet retarding means operating to slow down the speed of movement of the sheets by the transferring means to sub- 110 stantial accord with the speed of the second means for operating upon sheets before the sheets are delivered to said second means.

In testimony that we claim the foregoing 115 as our own, we affix our signatures.
